UNITED STATES PATENT OFFICE

161,996

STOCKING

Charles B. Biehl, West Grove, Pa., assignor to David D. Goff, C. David Goff, and Alexander N. Rubin, a partnership doing business as Dutchess Hosiery Mills, West Grove, Pa.

Application May 3, 1949, Serial No. 2,393

Term of patent 14 years

(Cl. D47—7)

To all whom it may concern:

Be it known that I, Charles B. Biehl, a citizen of the United States, and a resident of West Grove, county of Chester, State of Pennsylvania, have invented a new, original, and ornamental Design for a Stocking, of which the following is a specification, reference being had to the accompanying drawings, forming a part thereof, wherein:

I claim:

The ornamental design for a stocking, as shown.

CHARLES B. BIEHL.
